DESK

Charles E. Jones, Chicago, Ill., assignor to Rockwell-Barnes Company, Chicago, Ill., a corporation of Illinois

Application October 21, 1949, Serial No. 5,635

Term of patent 14 years

(Cl. D33—7)

To all whom it may concern:

Be it known that I, Charles E. Jones, a citizen of the United States, residing at Chicago, in the county of Cook and State of Illinois, have invented a new, original, and ornamental Design for a Desk, of which the following is a specification, reference being had to the accompanying drawing, forming a part hereof.

In the drawing:

Fig. 1 is a perspective view of a desk showing my new design;

Fig. 2 is a side elevation;

Fig. 3 is an end elevation; and

Fig. 4 is a top plan view.

I claim:

The ornamental design for a desk, substantially as shown.

CHARLES E. JONES,
